UNITED STATES PATENT OFFICE.

JEGENE T. TURNER, OF DAVENPORT, IOWA, ASSIGNEE, BY MESNE ASSIGNMENTS, TO
AMERICAN PLAYER ACTION COMPANY, OF NEW YORK, N. Y., A CORPORATION OF
NEW YORK.

PIANO-PLAYER.

Specification of Letters Patent. Patented May 26, 1914.

098,136.

Application filed November 13, 1909. Serial No. 527,918.

all whom it may concern:

Be it known that I, EUGENE T. TURNER, citizen of the United States, residing at Davenport, in the county of Scott and State of Iowa, have invented a new and useful improvement in Piano-Players, of which the following is a specification.

My invention relates to improvements in piano players, and has special reference to the provision of improved mechanism for producing a vacuum and the valve mechanism connecting therewith, leading both to the playing mechanism proper, and to the motor.

The object of my invention is the provision of simple and effective mechanism disposed in a compact and substantial manner, which will accomplish a considerable economy of space in installation. I attain this object by the mechanism illustrated in the accompanying drawings, in which,

Figure 1 is a front elevation of my improved mechanism, partially in section, disposed in the position in which it is easily installed in a piano. Fig. 2 is a side elevation of the bellows, carrying the motor valve case; and Fig. 3 is a rear elevation of the mechanism shown in Fig. 2.

Similar reference numerals refer to similar parts throughout the several views.

The reference numeral 1 designates a base-board, which, in upright pianos, is secured vertically in the portion of the case below the key-board. The base-board, 1, is secured firmly in position, and carries all of the mechanism hereafter to be described, except the communicating air conduits, which lead between the bellows and from the bellows to the piano player proper and the motor.

Extending inwardly from one corner of the bottom of the base-board, 1, is the arm, 2, which has the stop or lug, 3, at its rear extremity.

Attached to the rear face of the base-board, 1, by means of the bellows-fold, 4, is a movable bellows-board, 5. The bellows-board, 5, has extending from its lower edge an arm, 6, which communicates by means of a link, 7, and rod, 8, with the foot-treadle, 9.

The base-board, 1, is provided with a suitable number of perforations, 10, and over these is secured loosely by means of screws, or tacks, 11, a flexible piece of leather, or

other suitable material, 12, so as to form a valve, which will permit air to be expelled through the holes, 10, but will prevent ingress of air into the bellows therethrough.

A spring, 13, is secured between the bottom of the board, 5, and the lug, 3, upon the arm, 2, so as to normally hold the board, 5, closely adjacent to the base-board, 1, and to return it to that position after it has been moved backwardly therefrom, through the agency of the foot-treadle and the members connecting it with the arm, 6.

In position to come adjacent to one side of the board, 5, is another bellows-board, 14, secured to the bellows-board, 5, by bellows-folds, 15. The bellows-board, 14, has 70 extending from one portion thereof an arm, 16, and between the arm, 16 and a casing, 16^a, in which is the wind-passage, 17, to be presently described, is a spring, 18, which normally holds the bellows-board, 14, away 75 from the board, 5, and maintains the bellows, formed between said boards, in an extended or open position. The bellows between the boards, 14, and 5, opens into the rear of the bellows between the boards 5 and 80 1, and has a valve, 19, shown in Fig. 1, similar to the valve, 12, for preventing the passage of any air into the extended bellows from the first-described bellows. Located 85 upon the back of the board, 5, adjacent to the bellows formed by the board, 14, is the casing, 16^a, containing the wind passage 17, which connects with said bellows by means of the aperture, 20, clearly shown in Fig. 2. The object of providing this secondary, 90 spring-opened bellows, is as follows: When the first-described, larger bellows, is actuated, it withdraws air from the secondary bellows, and causes the spring, 18, to be contracted, and the bellows to collapse. While 95 the larger bellows is recovering for another stroke, the operation of the spring, 18, causes the distention of the second bellows, and maintains a continual suction of air.

As clearly shown in Fig. 1, structures as 100 have just been described, are provided upon both sides of the piano.

Located on the top of the base-board, 1, on the respective bellows at either side of the piano, are the valve cases, 21 and 22. 105 The valve case, 21, leads to the motor, and is arranged as follows: In one side of the back of the valve-case is provided an opening, 23,

which is connected by means of a piece of flexible tubing, 24, or other suitable flexible connection, with the casing 16^a, and the wind passage, 17, from the small bellows. 5 The portion of the valve casing, 21, into which enters the opening, 23, is separated by suitable partitions, 26, from the rest of the valve chamber. I have designated this separated portion by the reference numeral, 27, 10 and a passage, 28, leads therefrom to the top of the casing. The passage, 28, leads into a small bellows formed by the bellows-board, 29, and suitable bellows-folds, and from thence through an aperture, 30, back 15 into another compartment, 31, provided in the valve casing, 21. The inner face of the bellows-board, 29, is provided with a conical plug, 32, which extends into the aperture, 30. An arm, 33, extends from the board, 29, 20 and a spring, 34, connects the arm, 33, with the top of the base-board, 1. The spring, 34, keeps the bellows-board, 29, and the bellows, in an extended position, and thereby normally maintains the plug, 32, out of the 25 aperture, 30. This last-described valve mechanism, is for the purpose of avoiding a sudden acceleration of the motor by means of an increased vacuum, which may be desired for the purpose of strengthening the 30 piano action, and its operation is as follows: Any excess of vacuum, or sudden vacuum, tends to cause a collapsing of the bellows-board, 29, against the action of the spring, 34. The collapsing of the bellows-board, 35 drives the conical plug, 32, into the aperture, 30, and thereby prevents the air from flowing therethrough. As will be perceived, the action of this mechanism is automatic, and tends to, and actually does, maintain a 40 regular and uninterrupted and unvaried vacuum or exhaust from the motor.

The small compartment, 31, opens through a conical aperture 35, into still another compartment, 36, in the valve casing, 21. The 45 compartment, 36, leads directly through the channel, 37, to the motor, (not shown). Extending through the side wall, and the partition, 26, of the valve casing, 21, is a valve rod, or stem, 38, upon which is a conical 50 valve, 39, extending into the conical hole, 35, before-mentioned. The valve stem or rod, 38, is connected with a lever arm, 39^a, the upper end of which extends to a position in front of the key-board of the piano, 55 where it can be conveniently operated.

When it is desired to accelerate the motor, and thereby the tempo of the musical composition which the apparatus is reproducing, the lever arm, 39^a, is operated, which 60 causes the withdrawal of the conical plug, 39, from the conical aperture, 35, thereby making a larger passage for the flow of the air from the motor into the vacuum created by the bellows, through the aperture, 35. 65 The conical structure of the plug and aper-

ture, together with the horizontal disposition of the valve and valve-rod, renders the action extremely easy and free from sticking.

The valve case, 22, is provided with but two compartments, 40 and 41. Into the compartment 40 opens the passage, 42, which leads from the bellows which carries the valve-casing, 22, and for the purpose of utilizing the excess vacuum created by the other bellows, upon which is mounted valve 75 casing 21, which is not required for running the motor, there is provided a tubing, 43, extending between the casings, 21 and 22, which also opens into the compartment, 40. The compartment, 40, opens into the compartment, 41, through the aperture, 44, and from the compartment, 41, leads the air-tube, 45, which extends to the key-operating mechanism, (not shown). An aperture, 46, is provided in the partition, 26, in the valve-casing, 21, between the compartment, 27, into which the bellows opens, and the compartment, 36, which is connected with the motor. The apertures 44 and 46 in the respective valve-cases, 21 and 22, are in horizontal alinement, and a valve-stem or rod, 47, extends between the same.

On one end of the valve rod, 47, is a valve, 48, which closes the passage, 44, and on the other end thereof is a valve, 49, disposed so as to close the aperture, 46, when the rod is operated to open the aperture 44. This construction is to facilitate the re-winding operation. When music is being produced, the passage 44 is open, and the passage 46 is closed. When it is desired to re-wind the 95 music, the valve-rod, 47, is operated, so as to close the passage, 44, and open the passage, 46, so that the air can rush immediately from the motor through the casing, 21, to the bellows, without going through the compartment, 31, and regulating mechanism and bellows heretofore described. As will be perceived, this will shut off the vacuum from the producing mechanism, and thereby stop 100 production of any notes or noises, while the re-winding is being accomplished.

Having described my invention, what I claim as new, and desire to secure by Letters Patent, is:

1. In a piano player, vacuum producing mechanism comprising a rigidly fixed base-board, a bellows carried thereby, yielding means for holding said bellows normally closed, another bellows carried by said first-mentioned bellows and communicating therewith, yielding means for holding said last-mentioned bellows normally extended, a valve casing carried by said base-board, and a flexible connection between said last-mentioned bellows and said valve casing.

2. In a piano player, vacuum producing mechanism comprising a rigidly fixed base-board, a bellows carried thereby, yielding means for holding said bellows normally 120

closed, another bellows carried by said first-mentioned bellows and communicating therewith, yielding means for holding said last-mentioned bellows normally extended, a valve casing carried by said base-board, and a flexible connection between said last-mentioned bellows and said valve casing, said valve casing comprising two fixed compartments and a collapsible compartment dis-
10 posed adjacent to each other, ports leading from said fixed compartments into said collapsible compartment, yielding means for maintaining said collapsible compartment normally distended, and means carried by
15 the movable portion of said collapsible compartment for varying the capacity of one of said ports.

3. In a piano player, a foot operable mech-

anism, vacuum producing mechanism actuated thereby and disposed on either side thereof, valve casings carried upon each of said vacuum mechanisms, an air conduit between said casings, a port in one of said casings leading to the piano playing mechanism, a port in the other of said casings leading to a motor, a valve rod extending between said ports, and valves carried upon the ends of said rod, disposed so as to close one of said ports while the other is open.

In testimony whereof, I have set my hand 20
in the presence of two witnesses.

EUGENE T. TURNER.
